J. C. DARNALL.
RACK FOR STERILIZERS AND THE LIKE.
APPLICATION FILED MAY 20, 1918.

1,309,117.

Patented July 8, 1919.

Inventor:

John C. Darnall,
by John Elias Jones,
attorney.

UNITED STATES PATENT OFFICE.

JOHN C. DARNALL, OF CINCINNATI, OHIO.

RACK FOR STERILIZERS AND THE LIKE.

1,309,117.

Specification of Letters Patent.

Patented July 8, 1919.

Application filed May 20, 1918. Serial No. 235,581.

To all whom it may concern:

Be it known that I, JOHN C. DARNALL, a citizen of the United States of America, and a resident of Cincinnati, in the county 5 of Hamilton and State of Ohio, have invented a certain new and useful Improvement in Racks for Sterilizers and the like, of which the following is a specification.

This invention relates to trays or racks 10 especially adapted for use in sterilizers or the like for supporting drinking-vessels and other objects that are intended to be put into a thoroughly sanitary condition for use, and its object is to provide a tray or pan having a 15 perforated or wire-mesh bottom with a suitable, removable grille that is adapted to elevate said drinking-vessels and other objects to be sterilized to a greater or lesser degree above said perforated or wire-mesh bottom 20 so as to reduce the supporting contact-points of said objects to be sterilized to a minimum and, at the same time, permit a free circulation 25 of the sterilizing-media from a generating or supply chamber or receptacle that delivers said media to the bottom of said tray and thence through the perforations or wire-mesh thereof into and around the objects to be sterilized that are supported on 30 said grille, and a further object is to provide an auxiliary-rack that is supported by the rim of said tray and is adapted to support thereon other objects to be sterilized or otherwise treated in a sanitary manner, the objects in the lower tier, supported by said 35 first-named grille, being adapted to extend through said auxiliary-rack and to telescope within the objects supported by said auxiliary-rack without contacting therewith, and a still further object is to provide still 40 another auxiliary-rack, made of light, thin wire or the like that rests with the least points of contact upon said second tier of objects to be sterilized and, in turn, is adapted to support a third tier of objects to be 45 sterilized or otherwise treated in a sanitary manner.

The details of structure, which are quite simple and inexpensive, will be fully hereinafter described in connection with the several views of the accompanying sheet of drawings, in which,—

Figure 1 is a perspective view of the lower tray embodying the base or main portion of my invention and containing a removable 55 grille in a perforated bottom thereof; Fig. 2

a transverse section taken on the line x , x , Fig. 1, but showing in addition thereto the tray slidingly-supported within the walls of a sterilizing-chamber, the latter having below it a steam-generating chamber or other 60 source of sterilizer-supply, and in this view still further showing the first and second auxiliary-racks for use on said first tray in supporting several additional tiers of objects to be sterilized; Fig. 3, a plan view of 65 one form of auxiliary-rack; Fig. 4, a transverse section, on line y , y , of Fig. 3; Fig. 5, a plan view of a modified form of light rack for use in the upper tier of racks; Fig. 6, a transverse section, on line z , z , of Fig. 5; 70 and Fig. 7, a transverse section of an auxiliary, topmost rack having right-angled pedestals adapted to duly support glasses telescoped upside down thereon.

1 indicates a tray or pan having longitudinal side-walls 2 and transverse end-walls 3, together with a perforated bottom 4, the latter being susceptible of substitution by a wire-mesh instead of the perforations, as occasion may require. The tray 1 is adapted 75 to be slid into and from place on angle-iron supports 5 that are mounted within a sterilizer-chamber 6 having side-walls 7 and a bottom 8. The bottom is centrally orificed at 9 and forms the top of a steam-generating 80 chamber 10, said orifice 9 forming an exit through which the sterilizing gas or steam passes upwardly into the sterilizing-chamber 6 and thence through the perforated or 85 wire-mesh bottom 4 of said tray 1 for circulation around the entire surface, inside and outside, of the drinking glasses 11 that are supported in inverted position on a grille 12 in the bottom of tray 1, such grille being adapted to support the rims of the glasses 90 slightly above the perforated bottom 4 and thereby reducing the points of contact between said rims and said perforated bottom to a minimum and simultaneously reducing 95 the covered surfaces in which germs might 100 lodge and thereby escape the sterilizing gases in the operation of the device. The said grille is made up of fine crossed-wires of sufficient strength and stiffness to support the 105 drinking-glasses thereon and to form the first tier of glasses for treatment in the device. Of course said tier of glasses may be substituted for other objects of a nature needing sterilization or other treatment for putting them in a sanitary condition for use, 110

it not being deemed necessary to particularize such other objects herein, drinking or beverage glasses being considered objects of the greatest moment in which the sterilizer 5 action is necessary. Said grille can, of course, be dispensed with if desired, but its use is preferred for the reasons stated.

In Figs. 3 and 4, as well as in Fig. 2, I have shown a very desirable form of auxiliary-rack for use in supporting a second tier 10 of drinking-glasses on the rim of the tray 1 and so that the said second tier of glasses may partially telescope or encompass the up-ended bottoms of the lower tier of glasses, 15 as best shown in Fig. 2, and without the said up-ended bottoms contacting with the inner surfaces of the said second tier of glasses, whereby the circulation of the sterilizer gases is not interfered with and especially 20 into the interior bottoms of all the glasses in each succeeding upper tier as well as in the first tier. Said auxiliary-rack, seen in Figs. 2, 3 and 4, is composed of narrow sheet-metal that is formed into a rectangular 25 frame 13 on the interior of which is provided a series of pairs of partitions 14 at either side the longitudinal center-line thereof, such pairs of partitions being arranged in double array and having longitudinal 30 connecting-ligaments 15, fastening-rivets 16 being used to connect said ligaments. Each pair of partitions 14 has its outer ends 17 connected by rivets 18 to said rectangular frame 13 and it is obvious that the series of 35 pairs of partitions at either side the said center-line of the frame 13 can be made of a single piece or narrow strip of sheet-metal, bent into the shape shown in Fig. 3, and the rack is adapted to be laid in place on 40 the upper rim of the bottom-tray 1, as shown in Fig. 2, with the said up-ended bottoms of the lower tier of glasses extending upwardly through the several pairs of partitions 14 and without the latter touching said glasses 45 but ready to receive and support the inverted second tier of glasses whose rims rest on the edges of the thin strip of material forming said partitions 14 with the points of contact reduced to a minimum and there- 50 by reducing the liability of germs lodging between the rims of the glasses and said edges of the partitions 14. The second tier of glasses can be readily removed from the tray 1 by using the rack 13 with its internal 55 partitions in doing so and such rack can be readily placed on the drain-board or elsewhere, convenient to the user of the glasses or the one dispensing the beverages that such glasses are to contain.

60 An auxiliary-rack, such as is shown in Figs. 5 and 6, may be used in connection with the second tier of glasses, seen in Fig. 2, and adapted to support a third tier of glasses or other objects to be sterilized or 65 otherwise treated in a sanitary manner for

use. This last-named auxiliary-rack is composed of a rectangular frame 19, two longitudinal rows of rings 20 and a suitable number of hook-links 21, the latter being arranged both transversely and longitudinally 70 so as to couple said rings in alining rows parallel to the longitudinal side-members of the rectangular frame 19. In use, this last-named auxiliary-rack is adapted to rest upon the second tier of glasses with its rings 75 20 in the slightest possible contact with the outer surfaces of said glasses and vertically alining with the spaces between the double partitions 14 of the first-named auxiliary-rack, and it is preferably made of very light 80 wire that is strong enough to support the tier of glasses placed thereon for sterilization and for carrying them to using-position, corner-legs 22 being provided to support said last-named rack on drain-board, 85 table or the like for ready access thereto by the user. Said corner-legs 22 are preferable but not essential, and it will be seen that they will support the glasses at a higher elevation above the said drain-board than 90 will the turn-down hook-ends 23 without them, and with a more convenient hand-hold for elevating and carrying the rack.

The telescopic feature of the glasses seen in Fig. 2 is a very desirable one, as well as 95 important, for the reason that it saves space and makes the device more compact, as well as less liable to topple over or upset when in a sterilizing-chamber or otherwise.

An important feature of my invention resides in the auxiliary, topmost rack seen in Fig. 7 that is adapted to rest on the auxiliary-rack seen in Figs. 5 and 6, and to readily accommodate glasses having either bell-shape or straight bodies. This top rack is 100 made of flat sheet-metal crossed strips, each bent at right-angles to form upright pedestals 24 spaced by bases or feet 25. Channeled clamp bars or strips 26 engage the outer feet 25 of the pedestals and serve to 105 duly strengthen the structure for its desired use.

I claim:—

1. A sterilizer-rack comprising a main or bottom tray having imperforate sides 115 and a perforated or wire-mesh bottom, and an auxiliary-rack having a rectangular frame and one or more series of double, spaced partitions assembled within said rectangular frame and adapted to be 120 supported by the rim of said main-tray with the upper portions of the objects to be sterilized that are in said main-tray extending upwardly in the spaces between said partitions and the latter, in turn, 125 adapted to support objects to be sterilized thereon and in telescopic but not in touching engagement with the lower tier of objects to be sterilized.

2. A sterilizer-rack comprising a main or 130

- bottom tray having a perforated or a wire-mesh bottom, a grille or grating within said bottom and elevated slightly above same, an auxiliary-rack surmounting the rim of said 5 main-tray and having one or more series of spaced partitions therein for the vertical extension of the objects to be sterilized, supported in said main-tray on said grille and adapted to support a second tier of objects 10 to be sterilized that telescope without touching the lower tier of objects in the main-tray, and a second auxiliary-rack made up of light-wire rings that are connected within 15 in a light rectangular frame and adapted to but slightly engage the upper part of each of said second tier of objects to be sterilized for support thereon and such last-named light rack being adapted to support a third tier of objects to be sterilized and with or without the said second tier of objects to be 20 sterilized telescoping within the said third tier of objects to be sterilized.

JOHN C. DARNALL.
